ATTORNEY.

UNITED STATES PATENT OFFICE.

EDWIN JOHN KROEGER, OF AKRON, OHIO, ASSIGNOR TO JOHN R. GAMMETER, OF AKRON, OHIO.

RUBBER HEEL.

Application filed September 9, 1926. Serial No. 134,350.

This invention relates to rubber heels and methods for producing the same.

The general purpose of the invention is to provide a rubber heel construction with an insert through which nails can be driven anywhere and which will effectively prevent the heel from working off the nails, thus obviating forming heels with nail holes and using metal reinforcements, such as washers, or the like, about the nail holes.

Particularly, one object of the invention is to provide a light, inexpensive, highly resilient rubber heel of absolutely waterproof construction, including an insert of hard cellular rubber, such as vulcanized, hard sponge rubber, which may be vulcanized in the heel without special treatment to produce an integral heel construction, the cellular structure of the insert being such that a nail penetrating certain cells will not collapse the walls of adjacent cells, so that the insert will not split or crack.

Another object of the invention is to provide a rubber heel with a nail-receiving insert therein, both mechanically and chemically united with the body of the heel.

Another object of the invention is to provide a heel capable of being applied to foot-wear by automatic nailing machines.

Another object of the invention is to provide as an article of manufacture a rubber heel in which the nails have been started so that the cobbler need only apply the heel to the foot-wear and drive in the nails, handling of the nails thus being avoided.

Another object of the invention is to provide a method for producing the above heel. This method preferably comprises vulcanizing the heel with the insert, said insert being either previously completely or partially vulcanized or compounded of rubber capable of vulcanizing during vulcanization of the heel, the heel being vulcanized under such pressure as to prevent distortion of the heel by expansion of the gases in the cellular insert.

The foregoing and other objects of the invention are obtained by the heel construction illustrated in the accompanying drawings and described below. It is to be understood that the invention is not limited to the specific form thereof shown and described.

Of the accompanying drawings:

Figure 1 is a bottom plan of a heel embodying the invention;

Figure 2 is a top plan thereof;

Figure 3 is a section on line 3—3 of Figure 1;

Figure 4 is a section on line 4—4 of Figure 2; and

Figure 5 is a perspective view of the heel illustrated with the nails started, in which form the heels may be supplied by manufacturers.

Referring to the drawings, the numeral 10 designates the body portion of the heel which is of soft, tough rubber of the usual compositions such as heretofore have been employed.

During the process of vulcanization of the heel 10 an insert 11, preferably of an outline similar to that of the heel, is embedded in the top thereof, this insert preferably being formed of such material as vulcanized, hard sponge rubber either previously partly or wholly vulcanized or compounded rubber capable of vulcanizing hard during vulcanization of the heel. The inserts 11 may be obtained from sheets of vulcanized, hard sponge rubber of the required thickness as by punching the same therefrom.

The heel preferably is formed with a tread designed to define an area or areas in which nails may be driven, spaced ribs 12, 12 of the same general shape as the outline of the heel being shown formed on the bottom thereof, the outer rib substantially coinciding with the outline of the insert.

The heel 10 is made by mounting a blank 90 of soft rubber with the insert thereon in a mold adapted to exert pressure thereon during vulcanization such that the soft rubber will flow about the edges of the insert as illustrated at 13 to anchor the insert in the heel. The soft rubber also further interlocks mechanically with the insert by flowing into the broken cells in the edges thereof. In addition to the mechanical connection between the body of the heel and the insert, the two also become chemically united during the vulcanizing process as will be understood by skilled artisans.

The pressure employed during vulcanization is such as to prevent expansion of the 105 gases within the cells of the sponge rubber

from distorting the heel. As a further advantage, the pressure of the gas will compensate for the expansion of the rubber during vulcanization, so that no rind or overflow will occur, thus eliminating the usual trimming operations.

After the heels have been vulcanized, they may be shipped to factories for use on new footwear, the construction thereof permitting their effective application with automatic nailing machines, there being no specially located holes which the nails must find. When shipped to cobblers or for retail trade, the heels preferably are shipped with the nails started as shown in Figure 5.

It is to be noted that no special treatment of the hard sponge or cellular rubber is required so that it may be effectively bonded to the soft rubber of the heel, that it is both mechanically and chemically united

to the body of the heel and that in use it will not split or crack. The heel also permits of easy removal and replacement by persons who desire to change their rubber heels about because of uneven wear.

25

Modifications of the invention may be resorted to without departing from the spirit thereof or the scope of the appended claims.

What is claimed is:

1. A soft rubber heel having a nail-receiving insert secured therein during vulcanization thereof, said insert being of vulcanized hard sponge rubber.
2. A soft rubber heel having a nail-receiving insert secured therein, said insert being of vulcanized hard sponge rubber.
3. A soft rubber heel having a nail-receiving insert of cellular hard rubber secured therein.

EDWIN JOHN KROEGER.
